US00D622685S

(12) **United States Design Patent**
Garra et al.

(10) **Patent No.:** **US D622,685 S**
(45) **Date of Patent:** **** Aug. 31, 2010**

(54) **COMMUNICATION DEVICE**

(75) Inventors: **LanTing L. Garra**, Sunrise, FL (US);
Craig F Siddoway, Davie, FL (US)

(73) Assignee: **Motorola, Inc.**, Schaumburg, IL (US)

(**) Term: **14 Years**

(21) Appl. No.: **29/350,630**

(22) Filed: **Nov. 20, 2009**

(51) **LOC (9) Cl.** **14-03**

(52) **U.S. Cl.** **D14/137**

(57) **CLAIM**

The ornamental design for a communication device, as shown and described.

DESCRIPTION

FIG. 1 is a front perspective view of an ornamental design for a communication device;

FIG. 2 is a rear perspective view thereof;

FIG. 3 is a front view thereof;

FIG. 4 is a rear view thereof;

FIG. 5 is a first side view thereof;

FIG. 7 is a second side view thereof;

FIG. 7 is a top view thereof; and,

FIG. 8 is a bottom view thereof.

The broken lines that are immediately adjacent to the shaded areas, and define unshaded regions, represent the bounds, while all other broken lines are directed to environment and are for illustrative purposes only; the broken lines form no part of the claimed design.

1 Claim, 6 Drawing Sheets
